ATTORNEY.

UNITED STATES PATENT OFFICE.

JOHN ALEXANDER SHEARER, OF MILLSWOOD ESTATE, SOUTH AUSTRALIA, AUSTRALIA.

FAN.

1,420,155.

Specification of Letters Patent. Patented June 20, 1922.

Application filed May 12, 1920. Serial No. 380,906.

To all whom it may concern:

Be it known that JOHN ALEXANDER SHEARER, a subject of His Majesty, the King of Great Britain, residing at Forest Avenue, 5 East, Millswood Estate, in the State of South Australia, Commonwealth of Australia, has invented a certain new and useful Improvement in Fans, of which the following is a specification.

10 My invention relates to an improved hygienic fan, the object of the same being to so construct the component parts as to cause the air which is disturbed and deflected by the act of fanning to be passed through 15 louvers and to be thereby conveyed to a specially prepared surface containing means for deodorizing, disinfecting and perfuming the atmosphere.

In order to achieve the object of the invention the frame of the fan is so constructed 20 that it carries a movable member a surface of which may be treated with chemicals or scents suitable to the purpose above mentioned and above which fixed or movable 25 louvers are arranged and are set at an angle suitable for deflecting the air on to the prepared surface when the fan is in motion.

But in order that my invention may be more clearly understood I will now describe 30 the same by aid of the accompanying illustrative drawings wherein—

Fig. 1 is a front elevation of the fan with fixed louvers.

Fig. 2 is a side view of same.

35 Fig. 3 is a sectional side elevation.

Fig. 4 is a sectional plan or end view.

Fig. 5 shows a movable or interchangeable member for holding disinfecting deodorizing or other matter or chemical.

40 Fig. 6 is a front elevation of fan with hinged or movable louvers.

In each of the illustrations similar letters of reference are used to denote similar or corresponding parts wherever they occur 45 in the drawings.

In the drawings *a* is a fan-shaped frame, the back portion of which is covered by the portion *a*¹ shown in Fig. 3, the front being open. Beneath the frame a handle *b* is 50 formed.

A series of louvers *c* are mounted in the front portion of the frame or on both sides and may be either fixed as shown in Figs. 1 and 2 or they may be hinged as indicated 55 at *d* in Fig. 6 and are attached to an adjust-

ment bar *e* by means of staples or other device shown at *f* in the same figure. The adjustment of the louvers is already well-known in connection with window screens or shutters, and in my device I mount a 60 small bracket upon the handle and provide a holding pin as indicated at *g*, but any suitable form of fastening or cleat may be used.

The construction of the frame of my fan 65 provides a groove or receptacle more clearly illustrated at *h* in Figs. 3 & 4 of the drawings for the reception of the movable member *j* hereinafter referred to as the disinfecting plate which in size and shape neatly 70 fits into the grooved portion *h* as clearly indicated in the drawings. The disinfecting plate may extend slightly beyond the end of the frame and the plate is separately shown in Fig. 5 of the drawings. This 75 plate is provided with an extension *l* for the manufacture of which a narrow strip of whale-bone or the like may be used and is accommodated within the handle of the frame as shown in Fig. 3 and illustrations, 80 and may be gripped by any simple fastening device as for instance by the binding screw shown at *m* which is suitably mounted on a screw-threaded plate.

The disinfecting plate may be of cloth 85 fabric mounted upon thin wood or cardboard or stretched upon a thin frame or may be of any other suitable medium for the reception and absorption of deodorizing, disinfection, perfuming or cooling substance.

A modification of the structure to render the surface of the movable member more accessible is shown in Fig. 1 wherein a hinge *n* supports the louver portion of the frame, 95 a clasp being provided such as *m* on the opposite side thereof.

In applying my invention to practical use the disinfecting plate is sprinkled with the desired solution or chemical and is then passed into the receptacle formed in the frame, and its extension being accommodated in the handle it is securely held in position by the fastening device.

If the louvers are of a movable nature they are opened out to an angle of about 60° and are fastened in the desired position. When the fan thus arranged is waved against the air the air current passes between the parallel louver bars and is thus 110

2
thrown against the disinfecting plate and thus becomes purified or perfumed with each movement of the fan. If the louvers are of the fixed type they are set in the 5 position indicated in Figs. 1 and 2 and will afford the result above described.

After the fan has been used the movable louvers can be closed up thus reducing the evaporation of the substances which are applied to the disinfectant plate.

10 In the foregoing specification I have described and illustrated my invention in accordance with tests which have given good results but I do not confine myself to the 15 size, shape or constructional details shown in the drawings, as it would be possible to get good results even if the disinfecting plate were entirely omitted and the deodorizing or other material were placed 20 on a fixed permanent pad beneath the louvers or otherwise provided for in conjunction therewith.

Having now fully described and ascertained my said invention, and the manner 25 in which it is to be performed, I declare that what I claim is:

1. In an improved hygienic fan, a frame having a receptacle for the accommodation of a disinfecting plate, and means to control 30 the access of air to the plate.

2. In an improved hygienic fan, a frame having a receptacle therein, louvers in the frame for deflecting the air current into 35 the receptacle, and disinfecting means within the receptacle.

3. In an improved hygienic fan, a frame having a receptacle therein, a back to the frame, and louvers in the frame for deflecting air currents into the receptacle.

40 4. In an improved hygienic fan, a frame

having a disinfecting plate therein, and adjustable means for controlling a current of air to the plate.

5. In an improved hygienic fan, a frame portion, a hinged portion, said hinged portion being provided with louvers, said frame portion and hinged portion being adapted to form a receptacle for the accommodation of a disinfectant plate.

6. In an improved hygienic fan, a frame 50 having a receptacle therein, a back to the frame, a disinfecting plate in the receptacle, and means to control the flow of air to the plate.

7. In an improved hygienic fan, a frame, 55 a back on the frame forming with the frame a receptacle for the reception of a deodorizing material, and louvers on the frame for controlling air currents to the deodorizing material.

60 8. In an improved hygienic fan, a frame, a handle on the frame having a cavity therein, a back to the frame forming with the frame a receptacle, a disinfecting plate within the receptacle having an extension fitting within said cavity, and means for holding the plate in position.

9. In an improved hygienic fan, a frame, a handle on the frame having a cavity therein, a back on the frame forming therewith a receptacle, a disinfecting plate within the receptacle having an extension fitting within said cavity, and means on the handle to engage said extension to hold the plate in place.

75 In testimony whereof I affix my signature.

JOHN ALEXANDER SHEARER.

Witness:

JOHN HERBERT COOKE.
